Martin Mottier of Baltimore State of Maryland

Prints Patent.

The schedule referred to in these letters Patent and making part of the same, containing a description in the words of the said Martin Mottier, himself of his improvement in Pumpy

To all to whom these presents shall come,

Be it known, That I, Martin Mottier of the City of Baltimore & State of Maryland, have invented a new and useful improvement in the Pump, & that the following is a full and exact description of the construction and operation of the said machine or improvement as invented by me, —

Fig 1. is a piece in my former Patent (which bears date of the twentieth day of May, one thousand and eight hundred and thirty) representing a fulcrum box attached to the pump stock, in which by the handle rests & operates. a. b. are two plates which join at the line c. d, by the hinge at e. f. is a section of the handle g. is the end of the neck receiving h, which is a section of the spear with a key, —

Fig 2. also of the former Patent is a section of the handle as f. & g. Fig 1. with the pin a, — the neck and pin are welded together forming one solid piece: the pin being shouldered square at the right & the handle driven on

Fig 3. of former Patent, is a section of the upper end of the spear, bent at a right angle, and prepared to pass thru the eye, as at Fig 1. — Fig 4, 4. of former patent, are hollow friction rollers adapted to the ends of the pin

Fig 5. of former patent, is the inside view of the fulcrum box Fig 1. without the handle & neck.

Fig 6. is an improvement on Fig 1. the mortise this which the handle passes, being so altered as to leave out the flange a,

Fig 5. & to extend the left side of the handle at the pin to come

J

249

in a line with the right side of the neck, a., is a hook instead of the hinge a., fig. 1, for easy ready dissection of fig. 7, the hook attached, — Fig. 8, section of fig. 6, a., shows a bolt to receive the hook fig. 7, — Fig. 9, shows a variation of fig. 7, b. — Fig. 10, a section showing a bridge a., as a substitute for the bolt a., fig. 8. — Fig. 11, the same as fig. 9. — Fig. 12, inside view of fig. 6, without the flange a., fig. 5. — Fig. 13, section of the handle and neck, adapted to fig. 6, — the left side of the handle being in a line with the right side of the neck, the two forming one solid piece, with the pin done in, in the original plan the handle & neck, being two distinct pieces, were subject to give way or come loose, — Instead of the left side of the handle being in a line with the right side of the neck, the form may be secured by the box being formed accordingly.

Fig. 14, side view of fig. 13. — a, on the upper side of the neck being in a line with (or a little lower than) b, on the lower side of the handle; the object of which is to prevent the neck from striking against the inside of the box.

Fig. 15, a variation of fig. 6, consisting of one solid piece
Fig. 16, inside view of fig. 15, without the handle.

Fig. 17 & 18, correspond with a. b. fig. 15. Fig. 17, is a cylinder thro' which the neck of the handle fig. 18, passes, the bolt fig. 19, enters at c. 15 passes thro' a b. 17. 18, and comes out at d. 15. — Fig. 20 is one of two rings or rollers which fit loosely in each end of the cylinder 17. Fig. 21 is one of two washers at each end of 17. — Fig. 22, is a variation of a. b. 15, a. b. two pieces as fig. 23. 24, one of which being a counter part of the other, formed to receive the section of the neck, and handle 25. Fig. 26, is a ring or roller adapted to the hole in 25, the pieces 23. 24 and the handle are bound together by ties as seen at the dots in 22. Fig. 27, a variation of fig. 6, intended to dispense with the hook. It consists of two pieces. Fig. 28. 29. 29, is taken from 28, & turned

over, showing two small projections, a, which fit into the mortise, b and which by means of the dovetail in the joint of the two pieces 28-29, the outer edge of the projection, c, of the piece 28, being forced so as to prevent the piece 29, from coming out without its being first pulled outward, at the top, and then lifted upward to detach it from 28. The front part of the bed in which the pin rests extends up about two thirds of the diameter of the pin, this the hole of 29 & 28, a bolt passing to bind the pieces together, Fig. 30 is a variation of 16, Fig. 31. is 30 turned over, a, a, mortise which receives two pieces, one of which is represented at Fig. 32. which is a nut with a shank, a, drove or screwed into or this the stock.

Fig. 32 is a variation of Fig. 18, consisting of one solid piece, having pivot-holes at each end to receive the point of two screws, one of which is seen at Fig. 34, which press into the hole a, Fig. 30, thence this 32, which has a screw hole in it adapted to the screw bolt 34 which is retained & partly supported by 32. The pivot and the hole in which it plays is a substitute for the pin and journal, Fig. 35. is an inner view of a variation of Fig. 15. the part of the plate next to the stock and back of the journal of the pin is taken away & the journals are kept in their places by the vertical caps, 36. 36. which are partly sunk into the stock and partly into the mortise a, a. & a, a, b, b, pieces riveted to or cast on the main plate and are intended to set into one or more staples fitted into a plate, which plate is fastened horizontally across the stock, the dotted lines 35. represent a slot extending to b, which may be cut entirely out of any of the pieces similar to it, in which case the piece 36 is intended as a door or cover for the slot & it may be secured by lugs, catches or other fixtures.

Fig. 37. represents a hollow metal top to the stock; consisting of two pieces joined at the flange a, a. or the flange a, a, Fig. 38. b, 38. a hinge c, c, c, c, hinged to receive screw bolts, b, 37. the part which fits into the top or box of the

Mar 9, 1833

242

stock. The hole in the part b, receives screw bolts to bind the stock to this part. The dotted lines a & d. 38, represent a continuation of the body, &c, when the part b. of. or b. 38 is not attached in which case the stock will be connected by the lines d. & b. the top of stock will be bound together by screw bolts as before described. Fig. a handle & as 39, any of the others may by adaptation be applied as the projection or seats for the pin or shaft of the handle which may be placed higher up or immediately at the connection of the flange, in which case the neck will play within the hollow of the cap. Fig. 39. 40. are varied forms of the handle and neck, c.c. 39. Spring supporting a roller b, against which the handle strikes, to give an easy reaction. the feet of the spring are fastened to the stock. Fig. 41 above 12, is a form of a spring for the same purpose in either this form, a circle, an ellipse or any other form would answer a good purpose. Fig. 102 is a section of a pump spear. a. a. parts of the pitmen adapted to the necks a. a. of 39. b. the working connection of the pitmen & the spear. Fig. 103. another form of the pitmen and spear, adapted to fig 102, or any other of the single necks a. 42. is the top of the spear, passing thro' a plate b, which is also seen at f 38. the plate may contain two or more plain or grooved rollers to guide the spear. 102. is a section of the spear which is designed to pass thro' the plate crossing the hollow of the cap, as seen at g 38.

Fig. 104 a cast iron spout of my former Patent, the peculiarity of which is that it may contain either one or two nozzles, one in the nozzle, cast in it, about one inch up, the other at the back within the stock, — The spout also contains two semicircular pieces, each of which half or about half closes the passage standing on opposite sides about two inches apart within the stock, —

Fig. 105 a new form of a spout with a four square passage the dotted lines from a. to b. represent a slice within the passage

(647)

207

which may be soldered to b, or it may stand this to c, with a grommet and the slide may be perforated, with holes between a, & b, as is a grating suspended by hinge, and may be used as a substitute for the slide. Fig. 46, another form of the spout having a curve as at a, giving a free vent to the fluid having the inner fixtures similar to those of 45.

Fig. 47, a culmine cap fitting over or within the angle of the spout secured by a bolt as at a, to be used when the slide & gratings at 45. are not applied. Fig. 48, another form of the spout. Fig. 49, another form of the spout with a passage square from a, to b; from b, to c, is a grating d, d, this perforated or grated plate. c, a suspended grating, a, a, a, in Fig. 50, represents the stock or head of the pump. The part b, is a broad ring in the bore of the stock c, c, & c, screw bolts binding the stock to the ring.

Fig. 51, a straining band embracing the pump stock a, a, b, b, passing this the band into the pump b, b, key wedge, each of which passes this between the band at the end of one piece of the band, and the bolt. Fig. 52, a vertical section of another form of the joint of the bands b, is the same as b, of 51, c, is the same as c, 51, except the addition of the branch, d, which embraces the key and bent end d, in Fig. 53, a piece in the former Patent which secures the band cap to the pump.

Fig. 54 another form for the same object; a, and b, screw & plate as substituted for the knee a 53, the screw at a 54, may enter the hole c, in the box Fig. 6, & be secured by a nut.

It may also drop into the slot, at the top of 15 or 16, in this case the plate b, 54 will crop under the flange, from e, to f, in Fig. 15. — The plate 54 may be let into the head of the stock near the bore, and as a substitute for the screw as there may be a screw bolt passing this the hole c, Fig. 6 into the plate b, Fig. 55, of the former Patent, was attached to the cap, & looks over the upper end of the box as at b, Fig. 6.

the bow a, under Fig. 13, is intended to secure the boy to the pump & to bind the stock. the bow from d. to d, passes round the pump but the part between d. & t, d. & t, pass thro' the body of the stock. Other the holes f.f. and are covered by nuts, this bow, may also be applied to secure the spout, and bind the stock at 145 or 146.

In my former Patent I employed screw bolts to prevent the stock from splitting, one was placed across just above the spout the just under the handle mortise; & one in each of the remaining angles just above. these bolts were simply screwed into the wood; which by reason of their resting could not afterwards be tightened, now place one bolt across the mortise about two inches below the cap. which not only prevents the mortise from spreading but serves as a check for the neck of the handle. The remaining bolts are situated as they originally were. In applying the bolts, I now make the hole considerably larger than the bolt, & insert into the wood a plain nut for the head of the bolt, to rest or turn against and insert another with a screw for the screw of the bolt to lodge into a. a. Fig 13. projection which enters into the stock on each side of the handle mortise to prevent the upper part of the fulcrum boy from playing or moving upwards by the motion of the handle as well as to brace the timber & to retain the mortise to its original width. Fig 56. is an apparatus by which the fire hose may be supplied with water by the pump a. a. are shanks which pass up thro' the cut b, by the sides of the nozzle; the key c. c. pass thro' the hole in the upper end of the shanks and rest on the flange of the nozzle and bind all firmly together,

Fig. 57 is for the same purpose applied to spouts with nozzle similar to those of 44, 145, 17; having a funnel mouth it is attached to the spouts by means of streaks of iron riveted on. Fig 58. is also an instrument for the same purpose adapted to the common wooden spout, I however cut

7471x

Mar 9, 1833

243

valves, in the nozzle. I also apply the common hydant plug or any other suitable one may be applied to any part of the pump for the purpose of supplying the Nozzles, a friction ring as 36. may also be applied to the eye of the neck & joint of the spars, - After a careful examination I believe the improvements, embraced in these drawings & descriptions to be my own invention, yet I wish it to be distinctly understood, that I claim nothing in either the principle, or the application which shall not prove to be my own & new,
